CLAIM

The ornamental design for a filling port for a ship, as shown and described.

DESCRIPTION

FIG. 1.1 is a right profile view of the design;

FIG. 1.2 is a top plan view of the design;

FIG. 1.3 is a bottom plan view of the design;

FIG. 1.4 is a left profile view of the design;

FIG. 1.5 is a low perspective view of the design;

FIG. 1.6 is a high perspective view of the design;

FIG. 1.7 is a front view of the design.

(Continued)

The broken lines in FIGS. 1.1 through 1.3 and 1.5 through 1.7 show portions of the filling port for a ship that form no part of the claimed design.
